UNITED STATES PATENT OFFICE.

GEORGE W. FORTIER, OF GRAND RAPIDS, MICHIGAN.

CURTAIN-FASTENER.

1,363,244.

Specification of Letters Patent. Patented Dec. 28, 1920.

Application filed November 5, 1920. Serial No. 421,819.

To all whom it may concern:

Be it known that I, GEORGE W. FORTIER, a citizen of the United States, residing at Grand Rapids, in the county of Kent and 5 State of Michigan, have invented new and useful Improvements in Curtain-Fasteners, of which the following is a specification.

The present invention relates to curtain fasteners, *i. e.*, means whereby curtains may 10 be releasably held in drawn or closed position; and its object is to provide such a device having spring-pressed curtain-holding arms, turnable on a fixed mounting to a position wherein the curtain may be re- 15 leased, and to other positions whereby the drawn curtain may be held by the arms, both being turned to a position at one side of their mounting, or to a second position wherein they are both turned to the opposite 20 side of their mounting; or to a third position in which the arms are turned to extend in opposite directions.

This and any other objects hereinafter appearing are attained by, and the invention 25 finds preferable embodiment in, the device hereinafter particularly described and illustrated by the accompanying drawings, in which:—

Figure 1 is a view in perspective of my 30 curtain-fastening device, and a fragment of a curtain, the arms of the device being turned in opposite directions;

Fig. 2 is a view of the same, but showing 35 said arms turned to another curtain-holding position;

Fig. 3 is a view of the device showing the arms in curtain-releasing position, and illustrating the body member of the device in central longitudinal section;

Fig. 4 is a like view, but showing the arms 40 in the position seen in Fig. 1; and

Fig. 5 is a face view of the device, the arms being in the releasing position seen in Fig. 3.

In the embodiment of the invention chosen 45 for illustration by the drawings and for detailed description in the body of this specification, my curtain fastener is shown secured in a fixed position, as to the side

of an automobile body 1, as by screws 2 extending through the laterally-extending base 3 of the body member 4 of the device. This body member has a recess 5 extending longitudinally thereof, in which recess a 55

slidable plunger 6 is spring-pressed out- wardly by a spring 7 seated in the recess

behind the plunger. A pair of arms 8, 9, are pivotally mounted co-axially at 10 on ears 11 of the body member, and have flat portions 12, 13, 14 adjacent their pivotal 60 mounting, against which portions the plunger 6 abuttingly contacts under the spring's pressure. These arms may be turned on their pivotal mounting to various mutually side-to-side positions, *viz.*: to the position 65 seen in Figs. 3 and 5, wherein the orifice 15 in the free edge of the curtain 16 may be passed over said arms to engage or release the curtain; to another position, seen in Fig. 2 in which both arms are turned, side 70 to side, to the left hand side of the body member 4, in which position they retain the curtain in drawn position. This positioning of the arms may be desirably adopted where they are passed through the curtain's 75 orifice adjacent its lower left-hand corner, as seen in Fig. 2; the arms may be also turned together to another like position, wherein they extend in a direction opposite to that shown in Fig. 2, particularly where 80 they are passed through an orifice at the lower right-hand corner of the curtain. The arms may be also (and usually are) turned to opposite positions, as seen in Figs. 1 and 4 after being passed through the curtain's 85 orifice. One arm 8 is desirably longer than the other arm 9 (as shown) to facilitate the ready separation of the arms when in their position seen in Figs. 3 and 5.

The recess may extend through the body 90 member 4, thus providing it with an open bottom which may be (if desired) closed by a plug 17. By this construction, the plunger 6 and spring 7 may be inserted into the recess 5 without removing the pivot 95 pin 10, and the inner end of the spring 7 will then abut against said plug, or against the part 1 on which the device is mounted in case the plug be omitted.

The invention being intended to be pointed out in the claims, is not to be limited to or by details of construction of the particular embodiment thereof illustrated by the drawings or hereinbefore described.

I claim:

1. In a device of the character described; a body member provided with means for securing it in a fixed position and having a recess extending longitudinally thereof; a pair of arms pivotally mounted coaxially on 110 the body member and turnable thereon to oppositely-extending positions and to three

mutually-side-to-side positions, viz., one position in which the arms are substantially parallel with the longitudinal direction of the body member, a second position in which 5 the arms are transverse to said direction and extend beyond one side of the body member, and a third position in which the arms are transverse to said direction and extend beyond the opposite side of the body member, 10 each arm having adjacent its pivotal mounting three flat portions adapted to yieldingly retain the arms in their said respective positions by the pressure exerted on said portions respectively by the hereinafter-mentioned spring; a spring in said recess exerting pressure on said flat portions respectively.

2. In a device of the character described; a body member having a laterally-extending 20 base pierced for receiving means for securing the device in a fixed position and having a recess extending longitudinally thereof; a pair of arms pivotally mounted coaxially on the body member and turnable thereon to 25 oppositely-extending positions and to three mutually-side-to-side positions, viz., one position in which the arms are substantially parallel with the longitudinal direction of the body member, a second position in which 30 the arms are transverse to said direction and extend beyond one side of the body member, and a third position in which the arms are transverse to said direction and extend beyond the opposite side of the body member, 35 each arm having adjacent its pivotal mounting three flat portions adapted to yieldingly retain the arms in their said respective positions by the pressure exerted on said portions respectively by the hereinafter-mentioned spring; a spring in said recess exerting pressure on said flat portions respectively.

3. In a device of the character described; a body member provided with means for securing it in a fixed position and having a 45 recess extending longitudinally thereof; a pair of arms of different lengths pivotally

mounted coaxially on the body member and turnable thereon to oppositely extending positions and to three mutually-side-to-side positions, viz., one position in which the arms are substantially parallel with the longitudinal direction of the body member, a second position in which the arms are transverse to said direction and extend beyond one side 55 of the body member, and a third position in which the arms are transverse to said direction and extend beyond the opposite side of the body member, each arm having adjacent its pivotal mounting three flat portions 60 adapted to yieldingly retain the arms in their said respective positions by the pressure exerted on said portions respectively by the hereinafter-mentioned spring; a spring in said recess exerting pressure on said flat 65 portions respectively.

4. In a device of the character described; a body member provided with means for securing it in a fixed position and having a recess extending therethrough in said member's longitudinal direction; a pair of arms pivotally mounted coaxially on the body member and turnable thereon to oppositely-extending positions and to three mutually-side-to-side positions, viz., one position in 75 which the arms are substantially parallel with the longitudinal direction of the body member, a second position in which the arms are transverse to said direction and extend beyond one side of the body member, and a third position in which the arms are transverse to said direction and extend beyond the opposite side of the body member, each arm having adjacent its pivotal mounting three flat portions 80 adapted to yieldingly retain the arms in their said respective positions by the pressure exerted on said portions respectively by the hereinafter-mentioned spring; a spring in said recess exerting pressure on said flat portions respectively.

In testimony whereof I have hereunto set my hand at Grand Rapids, Michigan, this 3rd day of November, 1920.

GEORGE W. FORTIER.
